UNITED STATES PATENT OFFICE.

DONALD B. GILLIES, OF BUTTE, MONTANA, ASSIGNOR TO RALPH BAGGALLEY, OF PITTSBURG, PENNSYLVANIA.

DEVICE FOR PROTECTING BLASTING-CAPS.

SPECIFICATION forming part of Letters Patent No. 746,262, dated December 8, 1908.

Application filed May 6, 1903. Serial No. 155,802. (No model.)

To all whom it may concern:

Be it known that I, DONALD B. GILLIES, of Butte, Silver Bow county, Montana, have invented a new and useful Device for Protecting Blasting-Caps, of which the following is a full, clear, and exact description, reference being had to the accompanying drawings, forming part of this specification, in which—

Figure 1 is a longitudinal section of the sheath. Fig. 2 is a side view, and Fig. 3 an end view, of a guide for inserting the cap into the sheath. Fig 4 is a sectional view showing the cap incased in the sheath.

In blasting operations, especially in mines where there are water-veins, many accidents have occurred by reason of the wetting of the explosive-caps which are used to explode the charges of dynamite. It is the practice in mining to explode the charges in a number 20 of blast-holes, and when one of them fails to explode it will remain unnoticed, but is apt to explode with dangerous effect when struck by a miner's pick or drill.

My invention provides means by which certainty of explosion of the caps is secured, and I effect this result by providing means for readily incasing the cap in a flexible waterproof sheath, preferably of rubber, which when fitted tightly around the cap excludes water from it and keeps it dry and fit for detonation under all conditions.

In Fig. 1 of the accompanying drawings, 2

represents the flexible rubber sheath, which in Fig. 4 is shown fitted around the detonating-cap 3, to which the fuse 4 is attached. The neck of the sheath is preferably contracted, as shown in Fig. 1, so that it will fit tightly against the cap or the fuse.

In Figs. 2 and 3 I show a device consisting of a tapering guide-frame composed of a slotted ring 5 and spring-arms 6, which I use for fitting the cap in the sheath. The spring-arms 6 of this guide-frame are inserted into the sheath, the cap is pushed between the arms, and the guide can then be withdrawn, leaving the cap incased in the rubber, as shown in Fig. 4.

I claim—

1. A guide for inserting a blasting-cap into a flexible sheath, said guide comprising spring-arms adapted to be inserted into the sheath and affording between them a passage for the cap; substantially as described.

2. A guide for inserting a blasting-cap into a flexible sheath, said guide comprising tapering spring-arms adapted to be inserted into the sheath and affording between them a passage for the cap; substantially as described.

In testimony whereof I have hereunto set my hand.

DONALD B. GILLIES.
